(57) **CLAIM**

The ornamental design for a garment including sensors, as shown and described.

DESCRIPTION

FIG. 1 is a front, top, perspective view of a garment including sensors, showing the new design;

FIG. 2 is a front elevational view thereof;

FIG. 3 is a right side elevational view thereof, the left side elevational view being a mirror image of the right side elevational view; and,

FIG. 4 is a top plan view thereof.

The broken lines shown in the drawings depict portions of a garment and/or sensors that form no part of the claimed design.

1 Claim, 4 Drawing Sheets
